Inventor:

Hubert W. Morgan

UNITED STATES PATENT OFFICE.

HUBERT W. MORGAN, OF WESTFIELD, MASSACHUSETTS.

COFFIN-HANDLE.

SPECIFICATION forming part of Letters Patent No. 352,096, dated November 2, 1886.

Application filed February 23, 1884. Renewed May 11, 1885. Again renewed April 5, 1886. Serial No. 197,924. (No model.)

To all whom it may concern:

Be it known that I, HUBERT W. MORGAN, of Westfield, in the county of Hampden, in the State of Massachusetts, have invented certain new and useful Improvements in Casket-Handles, of which the following, in connection with the accompanying drawings, which form a part hereof, is a full and complete description.

My invention relates to that class of handles usually denominated "bar handles," in which a wooden or metallic bar is supported by hinged arm on the casket, and is an improvement upon the handles patented to me August 9, 1881, No. 245,543, and to J. A. Lakin and myself jointly,

15 August 2, 1881, No. 245,203.

It consists in certain details of construction, as will be described, and pointed out in the claims.

In the accompanying drawings, Figure 1 is an elevation of the handle, the arm, and the ear by which the latter is hinged to the casket. Figs. 2 and 3 are respectively front and rear views of the ear. Fig. 4 is a section on the line 4 4, Fig. 2; Fig. 5, a section on the line 5 5, Fig. 25 1; Fig. 6, a side view of the arm as it is cast and before it is bent into shape to form the loop for the handle. Figs. 7 and 8 are face views of rings to be placed upon the bar or handle, the same being shown in section at *a b* in Fig. 1.

30 The objects of my invention are, first, to reduce the cost of manufacturing the wooden bars or handles, and, second, to simplify the construction and increase the strength of the supporting-arms; and these objects I attain in the manner and by the constructions hereinafter described.

The bars or hand-pieces of coffin or casket handles are usually of irregular shape—that is, with annular enlargements or rings and grooves 40 at various points in their length, for the purpose of ornamentation. In wooden handles as heretofore constructed these enlargements or rings have been formed integral with the bar by turning the whole out of a solid stick of wood. This necessitated the use of a stick of a diameter at least equal to the largest diameter of the finished handle, and all that part of the material between the largest diameter and the smallest diameter had to be turned out, involving a very considerable waste of material. I avoid the greater part of this waste by turn-

ing the rings or enlargements out of separate pieces and afterward slipping them on the cylindrical bar and securing them in their proper positions by glue or other suitable means. This 55 construction enables me to make a handle with annular enlargements or rings out of a much smaller stick than has been practicable heretofore, and to avoid all waste except that incident to reducing a square stick to cylindrical form. 60 Moreover, the size of the rings enables me to make them out of a lower grade of stock than that required for the bars, as the material for their manufacture can be cut from between knots and other imperfections which would 65 defeat its use for the longer bars. Another advantage resulting from making these rings separately is that it enables me to use the same cylindrical bars or hand-pieces in making handles of different styles or configurations by disposing the rings differently upon the bars or by using rings of different sizes or shapes. 70

A indicates the cylindrical bar or handle; *a* and *b*, two rings, and *c* the end or tip, which is also made separately and doweled into the 75 end of the bar A. After adjusting and securing the rings upon the bar A, the whole is covered with a suitable fabric to give the desired finish.

The construction of the ear or socket B, and of 80 the arm C, by which these two parts are connected together and attached to the coffin, is the same as that described in my patent of August 9, 1881, above referred to.

The ring or loop at the outer end of the arm, 85 which surrounds and holds the handle A, is made by bending the outer or thin end of the arm back upon the thick part, as described in the patent of Morgan and Lakin, also above referred to. In the latter case, however, the 90 bent portion was supported and held in place upon the thick portion or arm proper by a screw alone. In the present case I form a holding-lug, *c'*, at the end of the portion to be bent back, which lug fits into a recess, *c''*, made to 95 receive it in the under side of the thick part or body of the arm C. This lug relieves the screw *d* of all strain, as it effectually resists any tendency of the loop to open out under an outward pull upon the handle.

100 While I have shown the handle or bar A supported by a single arm in Fig. 1 of the draw-

ings, it is to be understood that ordinarily two such arms will be used—one at each end of the bar—leaving sufficient space between them for the hand of the bearer.

5 Having thus described my invention, I claim—

1. A coffin-handle consisting of the cylindrical body A and one or more separate rings placed thereon and suitably disposed to impart to the desired finish or style, as shown and described.

2. In a coffin-handle, a hinged supporting-arm for supporting the handle proper,

having a loop, c, formed at its outer end by bending the metal back upon itself, the end of the bent portion being provided with a holding-lug, c', which engages a recess, c", in the body C, and the parts retained in proper position by a screw, d, which passes through the bent end into the body of the arm, as and for 15 20 the purposes described.

HUBERT W. MORGAN.
